ELECTRIC DISCHARGE DEVICE

Leo R. Peters, Cleveland Heights, Ohio, assignor
to General Electric Company, a corporation of
New York

Application April 21, 1945, Serial No. 589,489

11 Claims. (CL 176—122)

1

This invention relates to electric discharge lamps and their electrodes, and aims at improving the operation and light-output maintenance of such lamps. Advantages which may be obtained include preventing or minimizing what is known as "spiralling" of the discharge; prevention of so-called "anode oscillations"; and prevention or minimization of "end-blackening" of the lamp envelopes around and near the electrodes, which renders the lamp unsightly and is strongly objected to by users. The invention is especially advantageous for lamps intended to be started "cold," or without adequate preliminary preheat of the cathode(s); for lamps in which the discharge current is relatively low, around some 100 milliamperes or less; for long, slender tubular lamps whose envelopes are of comparatively small diameter, including the recently evolved slender fluorescent tubes operating on high voltages with low currents; and for germicidal lamps.

The invention is also useful in conjunction with starting arrangements for discharge lamps.

For the purposes of my invention, I screen off one or both electrodes of a lamp by means of an openwork enclosure or screen, which has a suitable potential relative to the associated electrode. Perforated sheet metal, wire mesh screening, or even a helical coil of fine wire wound to a close pitch are illustrative types of conductive grillage or foraminous structure suitable in such a screen. While the high conductivity of metal is not necessary for the screen, nevertheless metal is generally the most convenient material. The screen may be kept at suitable potential by allowing it to "float" in the discharge while insulating it from the conductive lamp parts and circuits. Preferred means which I have devised for insulatively holding the screen in position away from the surrounding envelope wall are also described and illustrated hereinafter.

Various other features and advantages of the invention will become apparent from the description of species and forms of embodiment, and from the drawings.

In the drawings, Fig. 1 is a side view of a tubular fluorescent lamp conveniently embodying the invention, a mid-portion of the lamp tube being broken out and omitted; Fig. 2 is a fragmentary view of one end of the lamp on a larger scale, the lamp envelope and a screen around the electrode being shown in longitudinal mid-section; and Fig. 3 is a tilted side view of the lamp mount before sealing into the envelope, a somewhat modi-

2

fied screen being shown in longitudinal mid-section.

Fig. 4 is a diagrammatic view illustrating the application of my invention in conjunction with lamp starting arrangements.

Broadly speaking, the lamp illustrated in Fig. 1 is similar in construction and operation to low pressure positive column fluorescent or germicidal tubes now in general use, whose envelopes 10 are substantially filled by a diffuse discharge, and are permeable to the desired radiation of the lamp; although some of the details shown are particularly adapted for long, slender tubes operating on low current at high voltage, as mentioned above. As in ordinary low pressure positive column lamps, Fig. 2 shows the vitreous envelope 1 as comprising (for each end) a re-entrant tubular glass stem 2 with an inner end seal 3 of flat pressed type. Wires 4, 5 (one or 20 both serving as current leads) extend through the stem 2 and seal 3, and at one end of the lamp (at least) an inner exhaust tube 6 opens through the seal 3 and extends out through the stem 2 to its own seal 7. Electrodes 8, 8 in the ends of the 25 envelope 1 adjacent the stems 2, 2 may be supported from the latter, in whole or in part through connection or attachment to the wires 4, 5. The operating atmosphere in the envelope 1 may consist of gas or of some vaporizable and ionizable working substance, such as metal, or of both together, as, for example, inert rare starting gas like argon at a pressure of some 2 to 6 mm., and mercury to an amount exceeding what will vaporize during operation, indicated in Fig. 30 1 by a droplet 9. A suitable pressure of the mercury vapor during operation is of the order of 10 microns. In the case of a fluorescent lamp, the envelope wall 1 includes or carries a layer of luminescent material or phosphor excitable by the radiation from the discharge, this wall layer being indicated in Fig. 1 as an internal coating 10 extending substantially throughout the 40 length of the envelope.

The electrodes 8, 8 may be of any suitable or 45 preferred type(s) for either A. C. or D. C. operation, and either for hot starting after preheat or for cold starting without preheat, although the benefits of the invention are greater in the case of a cold-starting lamp, as already indicated. In 50 a cold-starting lamp, the wires 5, 5 may be useful as supports, but are usually not required to carry current. One form of electrode that is adapted for either hot or cold starting is disclosed in U. S. Patent No. 2,306,925 to Aicher. To 55 adapt the lamp for operation on either A. C. or

D. C., both the electrodes 8, 8 may be constructed as thermionic cathodes, although in D. C. operation only one of them need be emissive. As shown in Fig. 2, each electrode 8 comprises a tungsten wire filament wound in a coil or a coiled-coil and connected at its ends to the wires 4, 5 sealed into the stem 2, and preferably coated and activated with a charge of alkaline earth metal oxide(s), such as a mixture including barium and strontium oxides. To make the electrode more compact, the coil 8 is shown as bent into the form of a narrow arch rising from the clamps at the inner ends of the wires 4, 5.

In accordance with my invention as here illustrated, there is associated with each of the electrodes 8, 8 a screen 11 setting apart or closing off a space around the electrode that is substantially constricted as compared with the general cross-section of the discharge path afforded by the envelope 1. This space may conveniently be referred to as the electrode space. The screen 11 shown comprises an openwork or foraminous grillage forming a sort of enclosure around the electrode 8. Such an enclosure 11 may preferably be constructed as a tube of woven-wire mesh or screening, with an end wall 12 of the same character in front of the electrode, and with the rear screen end closed in behind the electrode, as by being blocked off by the stem 2. As shown, the screen 11 is cylindrical and fits around the cylindrical body of the stem 2 with a snug, tight fit. The grip of the screen 11 on the stem 2 is further enhanced by the elastic properties of the wire mesh and by the fact that as shown in Fig. 2 the stem press 3 is wider than the diameter of the stem and the screen, so as to distort the latter elastically to an elliptic form at 13, above its lower end, Fig. 2. In other words, the screen 11 locks over the wide stem press 3 elastically. If desired, the screen 11 may be more positively keyed on the stem by providing a small lug 14 on the edge of the press 3 to project through the wire mesh, or may even be sealed to the glass by fusion of the latter. In a lamp tube 1 of $\frac{3}{4}$ inch diameter operating on a current of some 50 to 200 milliamperes, good results have been obtained with a screen 11 of about $\frac{3}{8}$ inch diameter and about 1 inch to $1\frac{1}{2}$ inch long extending about $\frac{1}{2}$ to $\frac{1}{4}$ inch beyond the inner end of the stem 2 with its seal 3, and about $\frac{1}{8}$ to $\frac{1}{4}$ inch beyond the electrode 8, and formed of nickel wire of 0.007 inch diameter woven to provide about 20 meshes per inch.

I have found that when the screen 11 is kept at a suitable potential, positive to that of the electrode 8 when the latter is functioning as cathode, the screen prevents the usual "end blackening" of the envelope 1 around and near the electrode 8, which is produced during the cathode cycles of the electrode, while allowing the luminous or other radiation from the discharge to reach and pass through said wall, or to excite its luminescent layer 10. Thus the envelope wall 1 around the screen 11 appears substantially as bright as though the screen were not there. The simplest way of thus maintaining the screen 11 at a suitable potential is to insulate it from all electrical parts and allow it to "float" in the discharge, without any electrical connection whatever. Under this condition, the screen 11 acquires or assumes a potential which is negative to that of the discharge around it, but is positive to that of the electrode 8 when functioning as cathode. In fluorescent lamps containing argon and mercury that I have tested

on A. C., this screen potential is some 10 volts R. M. S., more or less, above the cathode potential. A proper positive potential of the screen 11 relative to the electrode 8 while functioning as cathode is essential; for if the screen is connected to the electrode so as to have the electrode potential, the screen is altogether ineffective against envelope darkening. Within reason, the size of the screen openings is unimportant: I have found screens as coarse as 16 meshes per inch just as effective as those so fine as 100 mesh. The presence of the screen 11 does not materially affect the voltage taken by the lamp or its energy consumption.

While the nature and causes of the usual "end blackening" or darkening of a discharge envelope wall near an electrode are not fully understood or agreed on by those skilled in the art, it is conceded that it is somehow due to matter reaching the walls from the electrode, or from its lead(s). Whether this matter is activating material, electrode material, or lead-wire material need not be decided; nor do I express any opinion whether this matter itself forms the darkening wall deposit, or combines with the wall material or phosphor coating to darken it, or somehow draws a darkening deposit of the vaporized working substance, such as mercury. But it is generally agreed that the loss of material from the electrode occurs very largely during starting of the discharge and while the electrode is functioning as cathode.

The prevention of end-blackening by the screen 11 is not a simple blocking of matter vaporized or sputtered from the electrode 8; for if the screen is electrically connected to the electrode so as to have the same potential, it ceases to be effective; and besides this, the openings of a 16-mesh screen are so large that it would offer little real obstruction to such particles. Neither does it appear to be a mere case of electrostatic attraction of particles from the cathode 8 or leads 4 to the screen 12; because the screen appears perfectly clean throughout the life of the lamp, and no increase in its weight has been detected by even the most careful weighing. It seems, therefore, that the screen 11 must somehow actually prevent departure from the electrode of matter such as ordinarily produces blackening.

End blackening is especially bad in lamps operating on high voltages, and on small currents of the order of some 50 milliamperes, more or less, and it is worse when lamps are started and extinguished very frequently. Since at starting the electrode is too cold for vaporization, while the cathode drop is very high, and remains so until the electrode heats up enough to yield thermionic emission to lower the drop, the opinion is widely held that end blackening is not much due to vaporization. Rather, it arises from sputtering of (negatively charged) particles of electrode and leadwire material(s) due to bombardment of an electrode while functioning as cathode by positive ions of the discharge when the voltage drop in the discharge closely adjacent the cathode (called the "cathode drop") exceeds what is known as the "disintegration voltage," amounting to about 20 volts (more or less) for a mercury vapor discharge and an electrode activated with alkaline earth oxides. In harmony with this is the fact that cathodes which are especially difficult and slow to heat up at low starting currents give bad end blackening.

It is my view that the action of the screen 11 to prevent end blackening is intimately related to the formation of positive ions, which concur with the electrons in carrying the discharge current. Situated in suitable proximity to the electrode 8, the screen 11 receives both electrons and ions of the discharge, which come together on the screen and neutralize one another. Thus the screen offers a certain resistance to the passage of the current and gives rise to the formation of more positive ions in its vicinity, resulting in an accumulation of ions that constitutes a positive space charge; and a voltage drop arises at the screen 11 to provide for this ionization. Formed in or entering the inner space around the electrode 8, some of the positive ions meet in part the ion requirements for the passage of current there. Accordingly, fewer ions need be formed close to the electrode 8, and so the cathode drop required to produce the smaller number of ions is lower. The net effect is that the voltage drops adjacent electrode 8 and screen 11 are both below disintegration or sputtering value; or, in other words, the screen 11 in effect divides the cathode drop which is ordinarily high enough in starting to produce sputtering into two parts neither of which ever attains the disintegration value.

It is in harmony with this, at least, that in operation the voltage difference between the electrode 8 and the screen 11 is about 10 volts R. M. S., since this means that the peak value of this voltage difference is above the required ionizing potential of 10.4 for mercury vapor, but below the above-mentioned disintegration value of some 20 volts.

By preventing sputtering of negatively charged particles in the envelope 1, the screen 11 also prevents or minimizes the spiral swirling appearance of the discharge in the tube, and of the light from its luminescent wall layer 10, which occurs when such particles get into the positive column of a discharge in a lamp containing gas, as distinguished from mere vapor. In addition, the screen 11 prevents rapid fluctuations of voltage drop and current close to an electrode 8 functioning as anode (whether in A. C. operation on commercial frequencies such as 60, 50, or 25 cycles, or in D. C. operation), which are known as "anode oscillations," and may be a cause of telephone interference due to fluorescent lamps. This prevention of anode oscillations I believe to be due to the positive space charge at the screen 11, which serves as a sort of equalizing reservoir of positive ions on both cathode and anode cycles, and thus obviates periodic excesses and deficiencies of ionization in the tube which give rise to such anode cycle oscillations.

Various modifications in the form, arrangement, and construction of the screen 11 may be made consistently with my invention, so long as it offers sufficient but not excessive resistance to the passage of current through the discharge atmosphere and constricts a space around the electrode 8, but does not cut off radiation to the envelope wall 1. For example, the shape of the screen might be varied considerably; portions of its walls might be imperforate, instead of foraminous (as, for example, the portion 12 in front of the electrode 8); and portions of its wall might be omitted or provided with fairly large openings. In particular, the front end wall 12 shown in Fig. 2 may be omitted as in Fig. 3 without destroying the effectiveness of the screen 11, or its rear end may be left open, or both. But

even with an end of the screen 11 open, the open-work character of its wall cannot be altogether sacrificed without making it an obstacle to the discharge: e. g., if it were simply made as a tube of imperforate material instead of wire screening, this tube would absorb more positive ions than the openwork structure does; while if the structure took the form of a mere transverse imperforate disc mounted close in front of the electrode 8, with an annular opening around its periphery, positive ions formed at the annular opening would be absorbed by the tube wall 1, as well as by the disc. In sum, an imperforate structure would not afford so large a net output of ions available for the current to the cathode 8 as does the foraminous screen 11, and either the cathode drop or the voltage drop at the structure would tend to be higher to compensate. Moreover, the imperforate structure would tend to shut off desired light or radiation from the tube wall 1.

The effectiveness of the screen 11 would be destroyed if its relation to the electrode 8 were such that a voltage drop above sputtering value were necessary at the electrode 8 to maintain ionization to carry the current, as, for example, if the screen were very large, or very far in front of the electrode 8. In general, the limit on the distance of the screen 11 from the electrode 8 is that it must lie well within the outer boundary of the Faraday dark space as this phenomenon would exist if there were no screen. Per contra, the screen affords the advantage of minimizing or even abolishing the Faraday dark space when the screen is close to the electrode. However, the screen 11 would be ineffective to prevent end blackening if it were so close to the electrode 8 and offered such great resistance to passage of current that enough ions were produced in the vicinity of the screen to make ion formation close to the electrode unnecessary; for in this case the voltage drop at the screen would tend to exceed sputtering value, just as does the voltage drop adjacent the electrode 8 in the absence of the screen, and with the same effect as regards darkening of the envelope 1. And, of course, the screen must not be so close to the electrode as to be overheated and fused, vaporized, or badly warped.

Fig. 4 illustrates my invention in conjunction with arrangements to facilitate starting the discharge, particularly in cases where the cathodes are not preheated. For this purpose, a connection 15 in parallel with the discharge path through the gas and vapor in the tube 1 is provided, from near one electrode 8 to near the other electrode 8. As shown, the connection 15 terminates at each end in a hollow or annular conductive structure 16 outside of the corresponding screen 11, here represented as a surrounding outer tubular wire mesh screen similar to the screen 11, but insulated from it. The connection 15 extending the length of the envelope 1 preferably outside the same, or suitably insulated if inside, may be a mere wire of such trifling resistance as to amount to a short circuit connection. For a 40 watt fluorescent tube of 1½ inch diameter 48 inches long, such as hereinbefore referred to, this arrangement has reduced the starting voltage more than 25%, from about 400 volts to 290 volts. If desired, the circuit 15 may be interrupted after starting has been effected.

It is an important advantage of using inner and outer screens 11 and 16 that high resistance in the circuit 15 is unnecessary to keep this

circuit shorting the main discharge path from preventing or "dimming" the direct discharge between the electrodes 8, 8; whereas if the outer screens are omitted and the circuit 15 connected directly to the screens 11, 11, a resistance of the order of $\frac{1}{4}$ megohm is necessary in said circuit 15 to prevent such shorting out of the main discharge. In effect, the inner screen 11 "blocks" the outer structure 16 from emitting electrons when the corresponding electrode 8 is functioning as anode.

What I claim as new and desire to secure by Letters Patent of the United States is:

1. In an electric discharge lamp, the combination with a tubular radiation-transmitting discharge envelope having reentrant stems, coacting electrodes and other conductive parts therein, at least one of which is thermionic, widely spaced apart lengthwise of the tube to provide for a long-gap positive column discharge through the envelope, and an ionizable operating atmosphere in said envelope having in operation a low pressure, resulting in a diffuse discharge substantially filling the envelope, of a foraminous electrically conductive screen in the envelope and supported exclusively by one of said stems and enclosing the sides and operating-end of the associated electrode and providing therearound a space that is constricted as compared with the general cross-section of the discharge path in the envelope, while allowing the radiation from the discharge to reach the envelope, said one stem holding said screen in position and insulating it from the conductive lamp parts.

2. In an electric discharge lamp, the combination with a tubular radiation-transmitting discharge envelope having reentrant stems, coacting thermionic electrodes and other conductive parts therein widely spaced apart lengthwise of the tube to provide for a long-gap positive column discharge through the envelope, and starting gas and ionizable and vaporizable metal in said envelope, of enclosures comprising conductive foraminous walls supported exclusively by said stems and enclosing the electrode sides and operating-ends thereof and screening off electrode spaces that are constricted as compared with the general cross-section of the discharge path in the envelope, while allowing the radiation from the discharge within the enclosures to reach said walls, said stems holding said foraminous walls in position away from said envelope walls and also insulating them from the conductive lamp parts.

3. In an electric discharge lamp, the combination with a tubular radiation-transmitting discharge envelope having reentrant stems provided substantially throughout its length with a luminescent wall layer excitable by radiation, conductive parts and coacting thermionic electrodes in the envelope widely spaced apart lengthwise thereof to provide for a long-gap positive column discharge through the envelope, and starting gas and ionizable and vaporizable metal in said tube affording in operating a low pressure resulting in a diffuse discharge producing radiation for exciting said luminescent layer, of foraminous metal screens in the envelope supported exclusively by said stems and enclosing the sides and operating-ends of said electrodes and screening off electrode spaces that are constricted as compared with the general cross-section of the discharge path in the envelope, while allowing the radiation to reach the envelope wall and excite their luminescent material, said stems holding

said screens in position away from the envelope wall and insulating them from the conductive lamp parts.

4. In a mount for a tubular positive column electric discharge lamp comprising electrical parts and containing an ionizable discharge atmosphere, the combination with a vitreous reentrant stem at an end of the tubular discharge envelope, and a thermionic electrode adjacent the inner end of said stem supported exclusively from the stem and having current lead means sealed into the latter, a screen of foraminous electrically conductive elastic material surrounding the sides and operating-end and spaced from said electrode and having its end fitted around the stem, whereby said screen is held in position as aforesaid and also insulated from the electrical parts.

5. In a mount for a tubular positive column electric discharge lamp comprising electrical parts and containing an ionizable discharge atmosphere, the combination with a vitreous stem having at its inner end a seal press wider than the stem, and a thermionic electrode adjacent the inner end of said stem supported from the stem and having current lead means sealed through said stem press, of a foraminous screen of elastic wire mesh surrounding the sides and operating-end and spaced from said electrode and having its end fitted around the stem and elastically distorted by said seal press, whereby said screen is keyed in position as aforesaid and also insulated from the electrical parts.

6. In an electric discharge lamp, the combination with a tubular radiation-transmitting discharge envelope, coacting thermionic electrodes therein widely spaced apart lengthwise of the tube to provide for a long-gap positive column discharge through the tube, and an ionizable operating atmosphere in said tube, of hollow conductive structures in said tube, around said electrodes, with means for electrically interconnecting said structures; and enclosures around said electrodes, inside said hollow structures, comprising conductive foraminous walls electrically insulated from the conductive lamp parts and circuits, and screening off electrode spaces that are constricted as compared with the general cross-section of the discharge path in the envelope.

7. In an electric discharge lamp, the combination comprising a tubular radiation-transmitting discharge envelope, a pair of electrodes therein, lead-in conductors for supporting said electrodes, an ionizable atmosphere having in operation a low pressure, and a foraminous electrically conductive screen around one of said electrodes electrically insulated therefrom and enclosing the sides and operating-end of one electrode and its associated lead-in conductors for defining a space therearound which is constricted as compared with the general cross-section of the discharge path in the envelope.

8. In an electric discharge lamp, the combination comprising a tubular radiation-transmitting discharge envelope, a pair of electrodes therein, means for supporting said electrodes in spaced relation comprising lead-in conductors, an ionizable atmosphere having in operation a low pressure, and a pair of foraminous electrically conductive screens each enclosing the sides and operating-end of a different electrode and being electrically insulated therefrom for defining a localized and constricted space about the associated electrode in order to establish between

the screen and the associated electrode during operation a voltage difference greater than the ionizing potential of said atmosphere and less than the disintegration voltage thereof.

9. In an electric discharge lamp, the combination comprising a tubular radiation-transmitting discharge envelope and having reentrant stems, a pair of electrodes therein, means for supporting said electrodes in spaced relation comprising lead-in conductors, and ionizable atmosphere comprising mercury and a starting gas having in operation a low pressure, and a pair of foraminous electrically conductive screens each supported exclusively by the associated stem and enclosing the sides and operating-end of a different electrode and its associated lead-in conductors and being electrically insulated therefrom for defining a localized and constricted space about the associated electrode in order to establish between the screen and the electrode during operation a voltage difference greater than the ionizing potential of mercury and less than the disintegration voltage thereof.

10. In an electric discharge lamp, the combination comprising a tubular radiation-transmitting discharge envelope and having reentrant stems, a pair of electrodes therein, means for supporting said electrodes in spaced relation comprising lead-in conductors, an ionizable atmosphere comprising mercury and a starting gas having in operation a low pressure, and a pair of foraminous electrically conductive screens each supported exclusively by the associated stem and enclosing the sides and operating-end of a different electrode and its associated lead-in con-

ductors and being electrically insulated therefrom so that during operation of the associated electrode as a cathode said screen floats at a potential positive with respect to said electrode by an amount greater than the ionizing potential of mercury but less than the disintegration voltage thereof.

11. A gaseous electric discharge device of the positive column type comprising an elongated tubular envelope having cooperating electrodes at its ends at least one of which is a thermionic activated cathode, a reentrant glass stem at one end of said envelope having lead-in conductors extending therethrough into said envelope and supporting said cathode, and a tubular wire screen having a portion thereof surrounding said cathode and lead-in conductors and another portion thereof elastically gripping the exterior surface of said stem whereby to be supported exclusively and directly by said stem.
